UNITED STATES PATENT OFFICE

102,692

DESIGN FOR A KNITTED FABRIC

Jack Markowitz, New York, N. Y.

Application December 9, 1936, Serial No. 66,406

Term of patent 3½ years

To all whom it may concern:

Be it known that I, Jack Markowitz, a citizen of the United States, residing at 1472 East 37th Street, in the county of Kings, city and State of New York, have invented a new, original, and ornamental Design for a Knitted Fabric of which the following is a specification, reference being had to the accompanying drawing constituting a part hereof.

The figure is a plan view of a piece of the knitted fabric showing my new design.

I claim:

The ornamental design for a knitted fabric substantially as shown.

JACK MARKOWITZ.
